UNITED STATES PATENT OFFICE.

JOHN JORDAN, OF LONDON, ENGLAND.

CARD-PRINTING MACHINE.

SPECIFICATION forming part of Letters Patent No. 449,420, dated March 31, 1891.

Application filed September 10, 1887. Serial No. 249,343. (No model.) Patented in England August 25, 1887, No. 11,585; in France September 3, 1887, No. 185,637; in Germany September 8, 1887, No. 43,206, and in Belgium September 12, 1887, No. 78,850.

To all whom it may concern:

Be it known that I, JOHN JORDAN, of 69 Rahere Street, Goswell Road, in the city of London, England, a subject of the Queen of Great Britain, have invented certain new and useful Improvements in Card-Printing Machines, (for which I have obtained patents in Great Britain August 25, 1887, No. 11,585; in Germany September 8, 1887, No. 43,206; in France September 3, 1887, No. 185,637, and in Belgium September 12, 1887, No. 78,850,) of which the following is a specification.

My invention relates more particularly to the class of printing-presses designed for printing cards and similar articles, and has for its object the production of a printing-press of simple construction for that purpose.

In order that my invention may be the better understood, I have appended the accompanying three sheets of drawings, in which—

Figure 1 is a front elevational view of the device according to my invention, with the inking-table removed, but its position indicated by dotted lines. Fig. 2 is an elevation 25 of the right-hand end of same with fly-wheel removed. Fig. 3 is a plan of the same. Fig. 4 is a side view with the right-hand upright removed. Fig. 5 is a detail view of the cross-head, plunger, roller-carriers, and 30 grooved cam. Fig. 6 is a vertical section of the same, showing inking-table. Fig. 7 is a vertical section of the plunger, cam, and adjusting-wedge. Fig. 8 is a sectional elevation of the fence and shield. Fig. 9 is a plan 35 and sectional elevation of the shuttle. Fig. 10 is a plan and elevation of the guides. Fig. 11 is a sectional elevation of the movable platen. Fig. 12 is an end elevation, and Fig. 13 is a plan, of the frame for use in printing 40 upon thin paper.

In a printing press or machine having the improvements according to my invention the frame or foundation is formed of two uprights J J, and a bed J' between such uprights. Cast with, bolted, or otherwise secured to the left-hand upright is a cross head or ease L, forming a hollow vertical cylinder with extensions. Into the said hollow cylinder fits a hollow cam-box or plunger Q, the 45 lower extremity of which is dovetailed, so as to engage with the back of chase S, in which

the types are arranged. The plunger Q may be prevented from turning by means of a groove q' or channel cut therein and a pin inserted in the cross-head L, or by other 55 equivalent device. A main shaft B, supported by the uprights J J and working in bearings, passes through the cross-head L and plunger Q. Attached to or forming part of such main shaft is a cam b, which latter, being within the cam-box or plunger Q, imparts, as the main shaft revolves, a reciprocating motion to the plunger or cam-box Q aforesaid, and so brings the types into contact with and withdraws the same from the 60 material to be printed. If desired, springs may be employed to obtain with greater rapidity the retrograde motion of the plunger.

The inking-table N, Figs. 2 and 6, comprises a sheet of metal, preferably bent so as 70 to form about two-thirds of a cylinder, fastened at the ends to two ribs or stays n n'. The inking-table is capable of lateral motion upon slides l, which form a portion of the cross-head L. Said lateral movement of the 75 inking-table may be obtained by means of the device hereinafter described. Two arms or roller-gates E E' (one of which E' is fixed rigidly to or forms part of the main shaft B, the other arm E being a strap-head, Figs. 1, 80 3, and 5, capable of revolving freely in a channel formed in the cross-head L) are connected by means of rods or bars M, Fig. 5. A suitable number of inking-rollers P are supported in slotted holes e e, cut in said arms E E', and 85 revolve freely around the cross-head or ease, alternately passing over the inking-table and the types. The inking-table may be bent inward at its lower extremities x x', as shown in Fig. 2, in order to permit the rollers to pass 90 freely from the types to the inking-table.

For the purpose of more completely mixing or breaking up the lines the inking-table N may be caused to move laterally upon the cross-head, and in order to obtain the complete reciprocating motion of said inking-table N two revolutions of the main shaft B are required, so that the position of the inking-table may be changed once during each revolution of the roller-arms with a "dwell" 95 100 while the rollers are passing over the inking-table. Said intermittent reciprocating mo-

tion may be imparted to the inking-table in the following manner: The cam C, which is a thick ring keyed or otherwise secured to the main shaft B, has formed around its periphery two grooves or channels $c c'$, Figs. 1, 3, and 5. Said grooves or channels run parallel with each other for a distance proportioned to the dwell which may be required of the inking-table during the passage over the same of the inking-rollers. The grooves or channels $c c'$ then cross each other at the point y, Fig. 1. Into these grooves or channels $c c'$ takes the shuttle O, (shown in detail in Fig. 9,) which is fitted into one of the ribs n' of the inking-table in such manner as to be capable of turning as a swivel. The main shaft B, with a cam C thereon, being revolved, the shuttle O travels along the said grooves, passing from one groove to the other at each revolution from left to right and from right to left. The lower part of the shuttle O is of semicircular form, corresponding with the bottoms of the grooves in cam C, and is made with tapering ends, so as to admit of its crossing from one groove in such cam C to the other without over-riding. (See Fig. 9.)

The above method of causing the reciprocating motion of the inking-table is that which I prefer; but the motion may be obtained by other equivalent means.

The platen T, Figs. 3 and 11, is a flat piece of metal which fits into a recess formed in the bed-plate J' in casting same; also, for further securing the platen in its position two pins t may be attached thereto, which may engage in corresponding holes in the bed-plate J'. (See Fig. 11.) This arrangement of the platen permits of its ready removal for the purpose of "making ready" or otherwise.

In order to regulate the motion of the cam-box or plunger Q to suit cards, envelopes, and other material of different thicknesses, I provide a wedge R, Fig. 7, furnished at each end with a screw r and mill-headed nut r' . The said wedge R is placed within the cam-box or plunger Q in the path of the cam b, and by means of this device the movement of the cam-box or plunger Q may be adjusted to the greatest nicety.

The inking-rollers P aforesaid may be kept in contact with the inking-table N by the elasticity of the material of which said inking-rollers are composed, and in order to secure a proper pressure of the inking-rollers upon the types I provide two lifters or bearers K, Fig. 4, extending from the back to the front of the machine and attached to small inclined brackets or projections $k k'$, Figs. 3 and 4, formed upon the frame of the machine, the other extremities of which lifters rest upon the inclined face of a fence U, the formation and functions of which will be hereinafter referred to.

Upon the spindles of the inking-rollers are fitted small wheels or runners $p p$, Figs. 5 and 6, which in the course of the revolution of the main shaft B are brought into contact

with the lifters or bearers K, and the inking-rollers are thereby pressed against the types in a well-known manner. I employ, however, a special device for adjusting the height of said lifters or bearers K, and thereby regulating the pressure of the inking-rollers upon the types, as will be hereinafter described.

An automatic feed of cards or other articles to be printed may be obtained in the following manner—that is to say, the cards, envelopes, or other articles which are to be printed are placed upon the bed of the machine J' in front of and rest against the fence U and between the guides V V, which guides are made adjustable, so as to admit of cards, envelopes, or articles to be printed upon of various lengths. The fence U, before mentioned, extends across the machine, and is preferably triangular in section, the apex pointing toward the rear of the machine and the base being vertical and to the front thereof. Said fence U is provided at its extremities with lugs for attaching the same to the uprights J J or to the bed J' of the machine. In the center of the fence U is a shield U', formed of a plate of metal capable of being raised or lowered, so as to admit of said shield being adapted to the thickness of the cards or other articles to be printed by preventing more than one card being passed thereunder at one time. The said shield may be held in its position by means of a set-screw, as shown in Fig. 1.

The guides V V, which pass under the fence U, rest upon the platen and extend toward the rear of the machine, are so formed at the front ends as to suit the shape or conformation of the fence U, and are furnished with adjusting-screws v' . Said screws v' perform the double function, first, of securing the guides V V in the desired lateral position so as to adapt them to the length of the various cards or other articles to be printed, and, secondly, they press the guides V V upon the platen T, thus preventing the article being printed from getting under said guides. The adjustable guides V V have secured to their inner edges, by means of springs v'' , longitudinal strips of metal v , Fig. 10, which press gently upon the cards or other articles to be printed. A thin metal plate or pusher H is attached to a stud h' , which latter is caused by the mechanism hereinafter referred to to move to and fro in a slot J, cast in the bed J' of the machine. In its rearward motion the pusher H pushes the bottom card under the shield u' and carries it rearward between the guides V V onto the platen T, said pusher H being of such width—that is, from back to front—that, the front portion thereof remaining under the pack even in its most rearward motion, there is no liability to draw on the return motion the remaining cards or envelopes out forward, and this permits of the pusher H being readily returned to its starting position.

The next rearward motion of the pusher H carries another card rearward into the printing position, thereby displacing the pre-

viously-printed card or other article, which operation is repeated with each revolution of the shaft B.

The employment of a plate H instead of 5 the claw, which is commonly used, possesses great advantages, inasmuch as the plate with its stud h' is easily detached and a longer or shorter plate substituted.

The reciprocating motion of the said pusher 10 H may be obtained in the following manner: A cam D, Fig. 4, keyed or otherwise secured to the main shaft B, works in a strap d, which strap is pivoted to the frame of the machine at e', and has formed at its lower extremity a socket, 15 into which fits, so as to be capable of turning, the fork e'', which spans and rests upon the rocking lever e'''. Said rocking lever e''' is pivoted to the under side of the frame J at F, and has toward its extremity a longitudinal slot formed therein, in which rides a pin g'', attached to a slider g, working in dovetails G G, fastened to the under side of the bed J'. The slider g is provided with a longitudinal slot, 20 into which fits the stud h', to which stud 25 h' is attached, as before mentioned, the pusher II. The object of the longitudinal slot in the slider g is to provide a means for regulating the position of the pusher II according to the varying width—that is, from back to front—30 of the cards, envelopes, or other articles to be printed, the stud h', to which said pusher II is attached, being tapped to take a set-screw h.

From the foregoing description it will be 35 seen that the revolution of the main shaft will impart the desired reciprocating motion to the pusher II.

When it is desired to print upon thin paper, I detach the guides, and also the pusher 40 H, with its stud h', and attach to the slider g a light metal frame W, Figs. 12 and 13, with its stud h''. Upon this frame W is stretched and secured a membranous sheet—such, for instance, as vellum, smooth paper, or the like—45 and in order to retain the paper to be printed in position and prevent it from being lifted by the type I attach to the said metal frame W grippers or frisket-fingers w; which (in their normal position being held up by means 50 of springs) are depressed as the metal frame is carried under the fence U. It will be obvious that a reciprocating motion will be imparted to the said metal frame by the said mechanism which is used for operating the 55 pusher H. The sheet intended to be printed is carried into the printing position, where it rests, owing to the peculiar formation of the cam D. It is then printed and on its return is lifted off and a fresh sheet substituted in 60 the well-known manner.

The means above referred to, and which I adopt for regulating the pressure of the inking-rollers upon the types, is as follows—that is to say: The outer surface of the fence U 65 presents an inclined plane upon which the forward ends of the lifters or bearers K rest. The rearward ends thereof being provided

with slots rest upon inclined or angular brackets or projections k k', Figs. 2, 3, and 4, formed on the back of the machine, the angular contour of which brackets or projections corresponds with that of the fence U. In order to increase the pressure, the bearers or lifters k k' are brought slightly forward, in which movement they travel up the inclined or angular surfaces above referred to, being secured in the desired position by means of screws or equivalent means.

Now, in illustration of the movements of the various parts of the improved press or 80 machine in accordance with my invention I will assume that the fly-wheel A, which is keyed upon the main-shaft B, is being rotated and that the inking-rollers P P are just upon the point of leaving the inking-table. Then 85 the relative positions of the various parts will be as follows—that is to say, the shuttle or clutch O will commence to move laterally toward the point y, where the grooves or channels in the cam C cross each other, carrying with it in its travel the inking-table N. During the interval in which the rollers are 90 off the inking-table the plunger or cam-box Q remains stationary and allows the rollers P to pass over and deliver ink to the types 95 in the chase S. As soon, however, as the rollers leave the types the pusher H, by means of the strap d, forked lever e'', and rocking lever e''', is carried rearward under the fence U, pushing rearward the bottom card, envelope, or other article of a pack into the printing position.

It will be seen that a printing-press made in accordance with my specification has a 100 large inking-surface, an easy method of adjustment of impression, simple and easy system of automatic feed for cards, &c., and is a machine capable of ready conversion from a card-printing machine with automatic feed 105 into a paper-printing machine with non-automatic feed, and vice versa.

It will be obvious that the machine may be furnished with a treadle attachment or may be driven by power, and that an ink-duct of the well-known construction may be supplied 110 thereto.

I claim as my invention—

1. The combination of uprights J J, to one of which is secured cross-head L, main shaft B, with roller-arm E' attached thereto, roller-arm E, turning in a groove cut in the said cross-head L, and inking-table N.

2. The combination of uprights J J, to one of which is secured cross-head L, main shaft B, with roller-arm E' attached thereto, roller-arm E, turning in a groove cut in the said cross-head L, inking-table N, cam b, and plunger Q, with chase S.

3. The combination of inking-table N, roller-arms E' and E², shuttle O, and cam C for imparting to the said inking-table reciprocating motion, with rotary shaft B, carrying said roller-arms and cam.

4. The combination of the fence U, guides

V, with set-screws v' , the fence and guides being arranged as described, so that the said guides may be held in any lateral position by means of the set-screws and also thereby 5 pressed down upon the platen.

5. The combination of main shaft B, cam D, strap d, with forked lever e'', rocking lever e''', slide g, and pusher H, substantially as described and shown.

In testimony whereof I affix my signature in 10 presence of two witnesses.

JOHN JORDAN.
